Inventor:

Gustave Leve,
Per Attys. *Reynolds & Helton.*

UNITED STATES PATENT OFFICE.

GUSTAVE LEVE, OF NEW YORK, N. Y., ASSIGNOR TO AZARIAH B. HARRIS,
OF SPRINGFIELD, MASSACHUSETTS.

VENTILATING APPARATUS FOR RAILWAY-CARS.

SPECIFICATION forming part of Letters Patent No. 373,898, dated November 29, 1887.

Application filed June 9, 1886. Serial No. 204,658. (No model.)

To all whom it may concern:

Be it known that I, GUSTAVE LEVE, of the city of New York, in the county and State of New York, United States of America, have 5 invented certain new and useful Improvements in Ventilating Apparatus for Railway-Cars; and I do hereby declare that the following is a full, clear, and exact description of the same.

The invention relates to that class of car-ventilators which provide for the drawing of air from the exterior into the car, purifying same, and then distributing it through registers to different parts; and my improvements have for their object to simplify and cheapen 10 the construction and arrangement of the ventilator, and to improve its operation without necessitating the provision of a large separate compartment to contain the apparatus. In other car-ventilators, arranged according to 15 the system first mentioned, ice-boxes or refrigerators and water-pans have been made an essential, while by my invention no such medium is needed, and very little alteration is required to adapt my invention to cars of all 20 classes now in use; and in every case the apparatus is the same, whether used in winter to supply pure warm air to the car or in summer to replace the vitiated air with a fresh purified supply from the outside.

25 My invention consists in combining, in a railway-car having an isolated heater, a filtering-chamber above the heater having an air-inlet opening directly into it, a heating-chamber surrounding the smoke-pipe of the heater 30 and communicating with the filtering-chamber, and a vertical flue which conveys the air to horizontal flues extending within the car, and having registers opening into the interior.

For full comprehension of my invention 40 reference must be had to the accompanying drawing, forming part of this specification, in which similar letters of reference indicate like parts.

The said drawing is a longitudinal sectional elevation of part of a car, clearly illustrating 45 the improvements.

A indicates the main body of the car, B the ordinary heater-chamber, and B' the partition dividing same.

50 C represents the stove or heater, of any usual type, having a smoke pipe or flue, C', extend-

ing up through the roof of the car, D showing part of the water-tank, and d' d'' the hot-water pipes connecting the tank and heater and passing through the flue E around the 55 sides of the car in the ordinary manner, e showing one of the registers or grated openings in said box.

F represents any suitable hood or funnel, located, by preference, on the car-roof, (although it may be at the side or end, if found desirable,) and either made with double flaring mouths, as shown, or adapted to turn on a swivel, so as to adapt itself to whichever direction the car may be moving in, and f is 60 a pipe leading from said hood to the interior of a box or chamber, G, formed in or partitioned off from the heater-chamber B. About midway in this box or chamber G, I place a shallow platform or box, H, having a grated 65 or perforated bottom, h, upon which I place dampened sponges K or other suitable air-filtering medium.

L is a hinged damper, (or slide, if preferred,) arranged to be adjusted by a handle projecting 75 through the side of the box, or in any other suitable way, said damper being, by preference, located near the bottom of the box G, to correspond with an opening, g, in the wall G', dividing it from another chamber, M, formed 80 around the smoke-pipe C' or upper part of the heater. This chamber M has connected to it a pipe or conduit, N, leading down to and forming a close junction with the box G containing the heating-pipes d' d''. At the points 85 where these pipes pass into the conduit N close joints must be formed.

The box or chamber G will have a suitable door, (not shown in the drawing,) and the conduit N may also have a damper, n, as 90 shown in dotted lines, if found desirable.

Although in the drawing I have shown the different chambers formed with metal-sheeted boards, it will be understood that the whole apparatus may be constructed of sheet metal 95 of suitable weight, and the different joints formed by soldering or riveting, the shape and precise arrangement of the chambers and conduit within the heater-compartment being also immaterial.

100 The external air forcibly enters the hood F as the car is traveling and passes through the

pipe *f* into the box or chamber *G*, being cleansed and purified from dust, cinders, gases, &c., by its filtration through the sponges or other medium upon the grating, passing thence 5 (the damper *L* being opened) into the chamber *M*, and, if there is a fire in the heater *C*, will be warmed by the heat radiated from the smoke-pipe *C'* before entering the conduit *N*, from which it passes to the flue *E*, and, by 10 means of the different gratings or registers *e*, is disseminated throughout the car.

The vivified air in the car passes off, as usual, through ventilators *O*, placed in the upper part of the side walls.

15 What I claim, and desire to secure by Letters Patent, is as follows:

In combination with a railway car having a

heater inclosed in an isolated chamber, and flues *E* for containing heating-pipes, an air-inlet pipe, an air-filtering chamber, *G*, communicating directly therewith, a heating-chamber, *M*, surrounding the smoke-pipe of the heater and communicating with the filtering-chamber, and a vertical flue connecting the heating-chamber with the flues *E*, the filtering-chamber and the heating-chamber being entirely separated from the chamber which contains the heater, substantially as described.

New York, May 15, A. D. 1886.

GUSTAVE LEVE.
